PISTON

John Flammang, University City, Mo., assignor
to The Sterling Corporation, St. Louis, Mo., a
corporation of Delaware

Application October 21, 1935, Serial No. 45,852

1 Claim. (Cl. 309—11)

This invention relates to pistons and more particularly to trunk pistons of aluminum or magnesium and their alloys such as may be used in internal combustion engines.

5 In the development of pistons of the character referred to, and particularly where such pistons are made of aluminum or magnesium alloys, difficulty has been encountered because of the fact that the thermal expansion of aluminum is much
10 greater than that of cast iron; accordingly, an aluminum piston will expand faster than the cast iron cylinder in which it works.

In pistons as heretofore constructed, some arrangements have been suggested to render the 15 piston skirt resilient and yielding, so that expansion upon rise of temperature may be taken up or compensated for by the resiliency or yielding of the skirt. Such resiliency or yield has been sought by slotting or cutting the skirt circumferentially and vertically so as to render certain portions thereof free to move without restraint by the adjacent portions. This, however, not only rendered the piston skirt comparatively weak so that it was eventually distorted, but the 20 yield of the unrestrained portions resulted in the restrained portions of the skirt bearing against the cylinder, resulting in wear in spots or zones.

One of the objects of this invention, therefore, 30 is to provide a piston of the character referred to wherein the expansion is not only compensated for but so controlled that the bearing of the piston against the cylinder wall will not be in spots or zones.

35 Further objects will appear from the following description taken in connection with the accompanying drawing in which:

Figure 1 is a side view of a piston embodying its invention.

40 Figure 2 is a similar view showing the side opposite that of Figure 1.

Figure 3 is a bottom view looking into the open end of the piston.

Figure 4 is a longitudinal sectional view taken 45 on line 4—4 of Figure 3.

Figure 5 is a fragmentary view of a portion of the same side of the piston as seen in Figure 1, showing another arrangement of the slot.

Figure 6 is a fragmentary view of a portion 50 of the piston showing still another arrangement of the slotting.

Referring now to the accompanying drawing there is shown a trunk piston having a head 1, 55 wrist pin bosses 2 and a skirt indicated generally at 3, the interior of the piston being provided

with the usual ribs 5 and 6 firmly connecting the wrist pin bosses with the head. The head is, as usual, made of slightly smaller diameter than the skirt and the latter is relieved in the regions of the bosses as by being formed with a slightly oval shape, the diameter A taken across the thrust or bearing faces being slightly larger than the diameter B taken along the wrist pin axis.

5 The skirt is connected with the head in the region of the wrist pin bosses in the manner described but is separated therefrom by a circumferential slot or slots 8 and 9 in the region or regions between the bosses. The circumferential slot or slots may be in the lower ring groove 15 as shown in Figures 1 and 2 or therebelow as shown at 80 in Figure 6 in which case the diameter of the skirt portion above the bottom of the circumferential slot or slots is reduced in the same manner as is the head.

20 The skirt may be provided with vertical slots 7 running generally along the skirt but terminating above the lower end 4 so as to leave the latter continuous. These slots may extend from a point substantially midway of the length of the skirt upwardly as shown in Figure 1 and may join the slots 8 at the top, the portion between the vertical slots thus forming an upwardly extending tongue. The slots 4 are preferably given an 25 inclination with respect to the axis of the piston in order to avoid scoring of the cylinder wall; such inclination may, however, be moderate as shown in Figure 1 so as to connect with the ends of the horizontal slot or the inclination may be greater as shown in Figure 5 so as to connect 30 with the circumferential slot at points between its ends. The circumferential and vertical slotting 35 may be only on one side as shown in Figure 1, but may be on both sides; thus Figure 5 may be taken as corresponding to Figure 2.

40 It has been found that when the tongue formed by slots 7 and 8 is entirely free of the adjacent portions of the piston so as to be capable of unrestrained movement it gives away under pressure incident to the operation of the piston in 45 the cylinder, to such an extent that the actual bearing of the skirt on the cylinder wall takes place at the points or zones 12 adjacent the tongue and in practice such bearing is readily indicated by worn spots or zones found on the 50 skirt after use. In order to overcome this difficulty, the upper end of the tongue is connected to and supported on adjacent portions of the skirt by means of narrow bridges 10, and these bridges may be formed by lugs cast on the inte- 55

rior of the skirt, a hole being preferably preliminarily drilled in each lug prior to vertical slotting in order to receive the saw as it cuts the slot 7. This is a procedure resorted to in slotting generally, as will be shown by preliminarily drilling holes at the ends of the vertical and horizontal slots. The bridges or lugs 12 merge into the skirts by fillets, as is usual in casting practice. The bridges may not only be formed by permitting 10 the metal of the skirt to flow into the mold so as to form these bridges of the skirt metal, but they may be formed of steel or other material placed in the mold and anchored in the casting by permitting the metal to flow therearound in 15 a manner usual in casting practice.

In the piston structure described, the action is believed to be as follows: The skirt is connected to the head in the regions of the wrist pin bosses but free therefrom in regions therebetween. The 20 expansion of the head upon rise of the temperature will be communicated to the skirt only at these points or zones of connection; accordingly the expansion of the head will impose upon the portions of the skirt in the regions of the wrist pin bosses, the corresponding expansion. This expansion, therefore, takes place in the regions of the wrist pin bosses only, as the skirt is free from the head on the transverse axis; accordingly, the expansion of the head will tend to 25 stretch, bend or distort the skirt along a diameter parallel to the wrist pin axis, namely, along the diameter B. As a result of this action, the skirt is contracted or drawn in generally on the transverse diameter A and this contraction tends 30 to compensate for the increase in the diameter A due to the thermal expansion of the skirt itself; accordingly diameter A measured between those faces of the piston which bear against the cylinder wall is maintained substantially constant, while the expansion along the diameter B 35 has been compensated for by the relief previously described, so that a practically constant seat in the cylinder is maintained. Where there is only one of the circumferential slots, such as 8 with the accompanying slots 7 and bridges 10 on one side of the piston, then the action is believed to be generally analogous to that described, but restricted in degree due to the absence of one of

the circumferential slots and its accompanying vertical slots and bridges.

In the preceding description, a theory of operation has been suggested; it is to be understood, however, that this theory has been suggested to facilitate the disclosure and that this invention is not to be limited to any given theory. In practice it has been shown that a piston constructed in the manner shown and described will operate satisfactorily if for a piston of a diameter of $3\frac{1}{8}$ inches of an aluminum alloy the piston is fitted with a clearance of 0.002 inch along the diameter A and with a relief of 0.012 inch along the diameter B and with the bridges of the construction as shown and described. 15

It is further obvious that various changes may be made in the details of construction within the scope of the appended claim without departing from the spirit of this invention; it is, therefore, to be understood that the invention is not limited 20 to the specific details shown and/or described.

Having thus described the invention, what is claimed is:

A trunk piston of the character described comprising a head, a skirt having a greater diameter in the direction of its thrust faces than in the direction of its wrist pin axis, wrist pin bosses connected to the head, said skirt being continuous at its lower end but provided with slots in the upper region, said slots comprising a circumferential slot adjacent the upper end of the skirt on a face between the wrist pin bosses, and two longitudinal slots in said face intersecting said circumferential slot and extending downwardly therefrom so as to define a tongue separated on 35 three sides from the remainder of the piston, and narrow bridges springing from the upper corners of said tongue and connected interiorly with adjacent skirt parts, said bridges being constructed and arranged to restrain inward movement of 40 the upper corners of said tongue and maintain the same in position such as to prevent the adjacent skirt parts from disproportionately wearing, said tongue being entirely free on three sides from adjacent skirt structure except for said 45 bridges at the upper corners.

JOHN FLAMMANG.
